UNITED STATES PATENT OFFICE.

RICHARD MAX EATON, OF NIAGARA FALLS, NEW YORK, ASSIGNOR, BY MESNE ASSIGNMENTS, TO THE GARFORD MANUFACTURING COMPANY, OF ELYRIA, OHIO, A CORPORATION OF OHIO.

COMPOSITE ELECTRIC SYSTEM.

1,138,739.

Specification of Letters Patent.

Patented May 11, 1915.

Application filed April 15, 1909. Serial No. 490,100.

To all whom it may concern:

Be it known that I, RICHARD MAX EATON, a citizen of the United States, residing at Niagara Falls, in the county of Niagara and State of New York, have invented certain new and useful Improvements in Composite Electric Systems; and I do hereby declare the following to be a full, clear, and exact description of the invention, such as will 10 enable those skilled in the art to which it appertains to make and use the same.

The invention relates to improvements in composite systems where a telephone and police system are combined.

15 In general the purposes are to provide a system in which the main station may be signaled from the various sub-stations; to provide a telephone circuit not interfering with this; and to provide means for signaling an itinerant attendant, such as a patrolman upon his beat. To accomplish the latter, I use a signal either placed within or controlled by apparatus placed within a protecting casing and located adjacent the 20 route of the attendant. The signal I employ is bright and attractive, such for example as an incandescent lamp within a casing, having lenses in its walls. These signals may be seen from a great distance and when 25 operated attract the attendant to the box in which telephones are placed. The signals are placed under control of the attendant at the central station. They are controlled over the conductors of the telephone circuit 30 without incapacitating the conductors and apparatus for the other operations for which they are used. The telephone and the apparatus for controlling the signals located at the sub-stations are placed in protecting casings. I prefer to place the lamps 35 and lenses in said boxes also.

Other objects of my invention are to provide these circuits in a non-interfering, operative way, with a minimum number of 45 conductors.

50 My invention will be best understood by reference to the following description when taken in connection with the accompanying illustrations, showing one specific embodiment thereof, while its scope will be more particularly pointed out in the appended claims.

Figure 1 is a view of the circuits used. Fig. 2 is a front elevation of the case with

the door open, showing the apparatus with- 55 in. Fig. 3 is a side elevation with the door closed.

Referring to Fig. 1, the metallic line conductors are shown at 2, and 3, which, together with the ground, constitute the main 60 lines of the system. The central station is shown at A with substations C and D. Any number of substations may be included. The main 3 is normally connected to ground at the central station through the electro- 65 magnet 11 and battery B. At each station the main 3 may be grounded through legs 12 by closing the normally open switches 13-13. Between mains 2 and 3 telephone sets 15, 15 are normally in open bridges 70 14, 14. Other bridges 16 containing the high resistance and impedance relay 17, are connected in parallel with the telephone sets at each substation. These relays control contacts 18-19 which are interposed in the 75 circuit of the lamps 20 which may be bridged across the electric light mains 21 and 22 or placed in a local circuit. At the central station, the mains 2 and 3 terminate in the switch springs 23 and 24 which normally engage with contacts 25 and 26, but which, when sprung outward, are adapted to engage the terminals 27 and 28 of the central 80 station talking set 29 which is connected through the leads 30 and 31 to terminals 27 85 and 28. A battery B² and an induction coil 32 in series are bridged across these leads and supply current for talking purposes. The contacts 25 and 26 are connected by conductors 33 and 36 with other switch 90 springs 33 and 34. The spring 34 normally engages with a terminal 37 of the grounded battery B. The latter springs when separated, engage terminals 38 and 39 of the battery B'. A source of current 42 is placed 95 in the light circuit.

Figs. 2 and 3 show a case 41 in which are housed the telephone set 15, push button 13, relay 17, the signal lamp 20 and the signal transmitter 4. The front of the casing is 100 hinged and carries a light transmitting lens 40. Other similar lenses are placed in the sides of the case. I contemplate the use of similar lenses in other parts of the case, as my purpose in using them is to distribute the 105 light so that it may be seen from all directions and at great distances. The glass in the lenses may be colored, prismsed, or other-

wise modified so as to readily attract attention.

The operation of my system is as follows: When the sub desires to call the central for talking, the button 18 is pressed until it contacts with 43, closing circuit G³—43—13—12—3—24—26—36—37—11—B—G. This energizes the magnet 11 and throws the drop. The central operator then throws a lever or button (not shown) in such a way that the springs 23 and 24 disengage 25 and 26 and contact with 27 and 28. This interrupts the circuit just traced, cutting off the line signal and bridging the operator's set across the mains 2 and 3. When the substation removes the receiver, a talking circuit is completed as follows: 29—31—27—2—14—15—3—24—28—30—29. Current is supplied by battery B² through the induction coil 32 whose function is to choke out the variations in the battery current. Should the central station, or the chief at the police station, as the case may be, have reasons for calling the patrolman, for instance, when notice of the commission of some crime has been reported and it is desired to notify all the policemen in order that they may exercise vigilance in endeavoring to intercept the criminal, he may do so by throwing the lever in the opposite direction. The following circuit will then be closed: B'—39—34—36—26—24—3—16—17—2—23—25—35—33—38—B'. This energizes the magnet 17 to close switches 18—19 and completes the circuit of the lamp 20. Magnets 17 are made of such high resistance that the energy of the battery B² is insufficient to operate them while their impedance is high enough to prevent short-circuiting the telephone current. When the lamps 20 are illuminated, light transmitted through the lenses to the various quarters of the horizon will attract the attention of the patrolmen or others authorized to answer, who will proceed to the telephone for instructions.

While I have described my system as used by a police department, obviously, I may employ it for any analogous purpose where itinerant persons or out-door stations are to be called and conversed with, such for example as railway employees along a railway, watchmen and the like.

Other forms of signal may be used, and it is obvious to those skilled in the art that numerous and extensive departures from the form and the details of the apparatus here shown, may be made without departing from the spirit of this invention, the same being herein shown solely for the purpose of clearly illustrating the specific embodiment shown.

I claim:

1. In a composite system consisting of a combined police and telephone system, the combination of a main station, a plurality

of substations, telephone talking sets at substations operating over said system, a single pair of conductors connecting all of the talking sets of said stations, lamp signals at said substations and self-restoring means at the substations connected to the conductors independently of the talking sets' connections controlling said lamp, said means being adapted to be simultaneously controlled by the attendant at the main station over said pair of conductors.

2. In a composite system, the combination of a main station, a plurality of substations, a pair of conductors connecting said stations, telephone sets at the substations connected to the conductors, a normally non-luminous signal at each substation controlled over said conductors, self-restoring means connected to the conductors at the substations independently of the telephone sets and means at the main station for simultaneously operating the self-restoring means at the substations.

3. In a composite electric system, a central station, substations, metallic conductors connecting the central and substations, telephone sets at the substations and means to bridge said telephone sets across said metallic conductors, a self-restoring signal controlling means at each substation connected to said metallic conductors independently of the telephone sets, said signal restoring means being impervious to telephone currents, a signal at each station controlled by the signal controlling means thereat, and when actuated visible from a plurality of quarters, and mechanism for simultaneously operating said signal controlling means from the central station.

4. In a composite system, the combination of a main station, a plurality of substations, a pair of metallic conductors connecting said stations, a telephone set at each substation, a bridge at each substation between the metallic conductors in which the substation thereat is connected, a lamp signal at each substation, a self-restoring relay at each substation controlling the lamp thereat and connected to the conductors independently of the telephone sets and mechanism at the main station for controlling the simultaneous actuation and retirement of said lamp controlling means at the substations.

5. In a composite system, the combination of a main station and a plurality of substations, a pair of conductors connecting said stations, a telephone set at each substation connected to said conductors, a lamp signal at each substation, means to supply current to said lamp signals, self-restoring means at the substations controlling said lamp signals, said lamp signal controlling means being connected to said conductors independently of the talking sets, mechanism at the main station for causing the simultaneous

actuation of the lamp signal controlling means at the various stations and means controlled at the main station for permitting a simultaneous self-restoring actuation 5 of said signal controlling means.

6. In a telephone system, the combination of a main station and a plurality of substations, a pair of conductors connecting said stations, a telephone set and a bridge of said conductors in which said telephone set is connected at each substation, a lamp signal at each substation, means including circuit conductors for supplying current to the lamp signals, a self-restoring relay at each 15 substation connected to said line conductors independently of the telephone sets, said relays controlling the lamp signals and being self-restoring, mechanism at the central station for supplying current to simultaneously 20 actuate the relays at the substations, and means at the main station for interrupting the supply of current to said relays, whereby they are permitted to self-restore themselves and cause the retirement of the lamp signals.
25. 7. In a composite system, the combination of a main station and a plurality of substations, a pair of line conductors connecting

said stations, a telephone set at each substation, a bridge of said line conductors at each substation in which the telephone set thereat 30 is connected, a lamp signal at each substation, means including current conductors for supplying current to said lamp signals, a self-restoring switch for each lamp in its current conductors, a magnet at each substation controlling the switch of the lamp at the substations, a second bridge of the line conductors at each substation in which the magnet thereat is connected, means at the main station for supplying current to said 40 magnets and thereby causing the simultaneous actuation of said magnets at the various substations on the line conductors and means for interrupting the flow of current to said magnets, whereby they are simultaneously self-restored and releasing the lamp controlling switches, thereby simultaneously restoring the lamps.

In testimony whereof I affix my signature in presence of two witnesses.

RICHARD MAX EATON.
